UNITED STATES PATENT OFFICE.

JOHN E. SEDERHOLM, OF ST. PAUL, MINNESOTA, ASSIGNOR TO AMERICAN HOIST & DERRICK COMPANY, OF ST. PAUL, MINNESOTA, A PARTNERSHIP COMPOSED OF F. J. JOHNSON AND W. O. WASHBURN.

DESIGN FOR A LOUD SPEAKER.

Application filed April 14, 1928. Serial No. 26,321. Term of patent 14 years.

To all whom it may concern:

Be it known that I, JOHN E. SEDERHOLM, a citizen of the United States, residing at St. Paul, in the county of Ramsey and State of Minnesota, have invented a new, original, and ornamental Design for Loud Speakers, of which the following is a specification, reference being had to the accompanying drawing, forming part thereof.

Figure 1 is a front view; and
Figure 2 is a side elevation.

I claim:

The ornamental design for a loud speaker, as shown.

JOHN E. SEDERHOLM.
